UNITED STATES PATENT OFFICE.

OTTO EWERT AND HERMAN L. MARBACH, OF CLEVELAND, OHIO, ASSIGNEES,
BY MESNE ASSIGNMENTS, TO FRANK R. FENNESY, OF NEW YORK, N. Y.

WICK FOR OIL-STOVES OR LAMPS.

SPECIFICATION forming part of Letters Patent No. 530,170, dated December 4, 1894.

Application filed February 25, 1892. Serial No. 422,811. (No model.)

To all whom it may concern:

Be it known that we, OTTO EWERT AND HERMAN L. MARBACH, citizens of the United States, residing in Cleveland, in the county of 5 Cuyahoga and State of Ohio, have invented certain new Improvements in Wicks for Oil-Stoves or Lamps, of which the following is a full, clear, and complete description.

Our invention relates to a wick composed 10 of mica in layers or laminæ arranged in close contact with each other and when so placed bound together, the capillary attraction drawing the oil to the top of the wick so formed, where it will burn without charring or destroying said wick.

Our present improvement consists in arranging such laminæ in divided or independent bunches, whereby the oil has more free access to the thin spaces between the laminæ 20 than it would have in those constructions in which the wick is undivided into bunches, enabling the thin capillary spaces to be fed laterally along the exposed edges of the bunches and a more abundant supply of oil 25 to be carried to the flame. Said bunches are also exposed at their sides and edges, any cotton or other covering being dispensed with, the bunches being connected in such manner that the oil supply to their edges, as afore- 30 said, is not obstructed.

That the invention may be seen and fully understood by others, reference will be had to the following specification and annexed drawings, forming part thereof.

35 Figure 1 is an elevation of a form of wick, such as is used in "Argand" burners. Fig. 2 is a plan view of same. Fig. 3 is a vertical, longitudinal section showing the wick in an "Argand" burner. Fig. 4 illustrates the flat 40 wick, being an edge view of same and Fig. 5 is a plan view of same in the burner tube.

Like letters of reference designate like parts in the drawings and specification.

Our improved wick is as hereinbefore 45 stated, composed of laminæ of mica, bound together by any suitable means, which will leave the bunches exposed at their edges and sides, as for instance fine wire (wire being illustrated in the accompanying drawings).

50 In the formation of a circular wick for "Argand" or circular burners, thin flat sheets

of mica are cut into narrow strips *a*, *a*, *a*, Figs. 1, 2, and 3. These strips are formed into bunches as shown and compressed by the wire *b*, which brings the strips of each bunch into 55 close contact with each other and forms a cylindrical wick, which is placed in the tube formed by the outer wall *c* and inner wall *d*, Fig. 3, and allowed to extend down into the oil, the surface of which is denoted by dotted 60 line *e*, Fig. 3. Capillary attraction will carry the oil to the top of the wick, where it may be ignited and will burn without charring or consuming the wick, owing to mica being non-combustible, which is a well known fact, the 65 wick being a conveyer of the oil to the point of ignition where the said oil is consumed without destruction to the wick.

In the formation of flat wicks, the sheets of mica may be cut the desired width and 70 two or more of them bound together as shown, Figs. 4 and 5. The wick is used the same as an ordinary cotton wick, being placed in the tube *h*, Fig. 5, and raised and lowered with the wheel *i*.

75 In our description we have simply described the wick as used for lamps. It will however readily be seen that the same wick can be used in oil stoves. It is therefore not deemed necessary to encumber the specification with 80 a detailed description of the wick in connection with stoves.

It is essential that the wick consist of a number of bunches of mica, each bunch consisting of a number of narrow strips or laminæ laid together and confined only with sufficient firmness as will provide the necessary capillary spaces between the laminæ up which the oil will be drawn. So, too, the laminated material should be actually separated into 85 strips or laminæ, it not being sufficient to rely upon the natural laminated structure of the material. By using small strips of mica inexpensive wicks may be formed by using waste material that has practically no commercial value at present. Of course the same bunch effect may be produced by using large sheets of mica and slitting it vertically into strips not wholly separated from the sheet, and by assembling a quantity of these partially 90 slitted sheets to produce the independent bunches referred to.

We are aware that it has been heretofore proposed to employ for lamp-wicks mineral wool inclosed in cotton textile material; also threads of fine-spun glass inclosed in cotton textile material; also mica rolled or doubled to form the wick; and we do not intend our claim to be understood as extending to wicks of such constructions. We have found by experiment that neighboring pieces of glass 5 have not sufficient capillary action to be practically effective, and that the mica to be most effective must be divided into bunches. 10

What we claim as our invention, and desire to secure by Letters Patent, is—

The herein described lamp or stove wick consisting of a number of independent bunches of laminated mica held together and exposed at their sides and edges, each bunch consisting of flat narrow strips held together with sufficient pressure to form capillary spaces 15 between them.

In testimony whereof we affix our signatures in presence of two witnesses.

OTTO EWERT.
HERMAN L. MARBACH.
